BRISTLE HOLDER FOR BROOMS

Eli Sacks, Hollywood, Calif.

Application February 3, 1950, Serial No. 7,706

Term of patent 3½ years

(Cl. D9—2)

To all whom it may concern:

Be it known that I, Eli Sacks, a citizen of the United States of America, residing at Hollywood, in the county of Los Angeles and State of California, have invented a new, original, and ornamental Design for Bristle Holder for Brooms, of which the following is a specification, reference being had to the accompanying drawing, forming part thereof.

Figure 1 is a perspective view of a bristle holder for brooms, showing my new design; Figure 2 is a side view of the bristle holder; Figure 3 is an end view of the bristle holder; Figure 4 is a top plan view of the bristle holder; and Figure 5 is a bottom plan view of same.

I claim:

The ornamental design for a bristle holder for brooms, as shown.

ELI SACKS.
